UNITED STATES PATENT OFFICE.

JOHN L. POPE, OF CLEVELAND, OHIO.

ADJUSTABLE WALKING-STILT.

SPECIFICATION forming part of Letters Patent No. 486,891, dated November 29, 1892.

Application filed May 19, 1892. Serial No. 433,633. (No model.)

To all whom it may concern:

Be it known that I, JOHN L. POPE, a citizen of the United States, residing at Cleveland, in the county of Cuyahoga and State of Ohio, 5 have invented certain new and useful Improvements in Adjustable Walking-Stilts; and I do hereby declare that the following is a full, clear, and exact description of the invention, which will enable others skilled in the art to which 10 it appertains to make and use the same.

My invention consists of a walking-stilt made according to the following description.

In the accompanying drawings, Figure 1 shows a perspective view of my stilt; Fig. 2, 15 a side elevation; Fig. 3, a longitudinal section of step when adjusted to slide on the shaft.

The step has the upper portion of the surface next to the shaft at an obtuse angle with the step-pad and the lower portion at a right 20 angle to said pad, which portion of surface is parallel to and rests against the shaft when in position for use. On the opposite side

from the step-pad of the opening through which the shaft passes is a bar which is caused to engage in notches in the shaft when in position for use. 25

Having thus described my invention, what I claim as new, and desire to secure by Letters Patent, is—

In an adjustable walking-stilt, an arm or 30 step having the upper portion of the surface next to the shaft at an obtuse angle with the step-pad and the lower portion at a right angle to said pad and a bar on the side of the opening through which the shaft passes 35 opposite the pad and notches in the shaft for the engagement of said bar, all substantially as described.

Witness my hand to the foregoing specification this eleventh day of May, 1892.

JOHN L. POPE.
